US00D523877S

(12) **United States Design Patent** (10) Patent No.: **US D523,877 S**
(45) Date of Patent: **** Jun. 27, 2006**

(54) **COOLING MACHINE**

(75) Inventor: **Reinhold Resch**, Liezen (AT)

(73) Assignee: **AHT Cooling Systems GmbH**,
Rottenmann (AT)

(**) Term: **14 Years**

(21) Appl. No.: **29/224,074**

(22) Filed: **Feb. 24, 2005**

(30) **Foreign Application Priority Data**

Aug. 27, 2004 (EM) 000219142

(51) **LOC (8) Cl.** **15-07**

(52) **U.S. Cl.** **D15/81**

(58) **Field of Classification Search** D15/79-88;

(57) **CLAIM**

The ornamental design for a cooling machine, as shown and described.

DESCRIPTION

FIG. 1 shows a front view of my design for a cooling machine;

FIG. 2 shows a side view thereof;

FIG. 3 shows an opposite side view thereof;

FIG. 4 shows a rear view thereof; and,

FIG. 5 shows a top view thereof.

The bottom view forms no part of the invention.
